DESIGN FOR A FISH LINE REEL

Reynold T. Hedfield, Madison, Wis.

Application May 4, 1945, Serial No. 119,384

Term of patent 14 years

(Cl. D31—4)

To all whom it may concern:

Be it known that I, Reynold T. Hedfield, a citizen of the United States, residing at Madison, in the county of Dane and State of Wisconsin, have invented a new, original, and ornamental Design for Fish Line Reel, of which the following is a specification, reference being had to the accompanying drawing, forming a part thereof.

Fig. 1 is a side elevational view of the fish line reel, embodying my new design;

Fig. 2 is a top plan view of the fish line reel shown in Fig. 1;

Fig. 3 is a sectional view taken along the line 3—3 of Fig. 2, and

Fig. 4 is a sectional view taken along the line 4—4 of Fig. 1.

I claim:

The ornamental design for a fish line reel, substantially as shown.

REYNOLD T. HEDFIELD.
